UNITED STATES PATENT OFFICE.

THOMAS A. DE VILBISS, OF TOLEDO, OHIO.

AUTOMATIC ARTICLE-COATING MACHINE.

1,070,428.

Specification of Letters Patent. Patented Aug. 19, 1913.

Application filed August 19, 1912. Serial No. 715,814.

To all whom it may concern:

Be it known that I, THOMAS A. DE VILBISS, a citizen of the United States, and a resident of Toledo, in the county of Lucas 5 and State of Ohio, have invented a certain new and useful Automatic Article-Coating Machine; and I do hereby declare the following to be a full, clear, and exact description of the invention, such as will enable 10 others skilled in the art to which it appertains to make and use the same, reference being had to the accompanying drawings, and to the characters of reference marked thereon, which form a part of this specification. 15

My invention relates to surface coating apparatus, and has for its object the provision of an improved apparatus of this character, which is automatically operable to success- 20 sively move articles into surface coating position, apply a surface coating material thereto, and then move them from such position.

A further object of the invention is the 25 provision in connection with an air brush, of fluid pressure operated means for controlling the opening and closing of the fluid and liquid valves thereof, whereby to enhance the practicability and commercial value of such 30 apparatus.

The invention is fully described in the following specification, and while, in its broader aspect it is capable of embodiment in numerous forms, a preferred embodiment 35 thereof is illustrated in the accompanying drawings, in which,—

Figure 1 is an elevation of a machine embodying the invention, with parts broken away. Fig. 2 is a top plan view thereof 40 with parts broken away. Fig. 3 is a top plan view of a portion of the driving mechanism. Fig. 4 is an enlarged sectional detail of the air valve and control parts. Fig. 5 is an enlarged sectional detail of a form of air- 45 brush used in connection with the machine. Fig. 6 is a side elevation of one of the parts which guide the vertical swinging movements of the work moving arms, and Fig. 7 is a cross-section of the cam-shaft with the 50 cams thereon.

Referring to the drawings, 1 designates a frame top or table which is supported by legs 2 and has a hollow standard 3 mounted thereon. A rotary work-supporting table 4 55 is mounted loosely upon the top of the standard 3 and has an annular flange 5 depending

from its underside and loosely encircling the cylindrical upper end portion of the standard which forms a journal therefor. The lower edge of the table flange rests upon 60 anti-friction rollers 6, which are mounted in suitable brackets on an annular ledge or flange 7 on the standard, thus supporting the table for free rotary movements. The table 4 is provided with a central opening 8, which 65 is concentric to the flange 5, and has its top surface preferably formed with a series of spaced radial ribs 9 upon which an article rests when being coated.

The table flange 5 has an annular series of 70 teeth, which form a gear 10, and this gear meshes with and is driven by a gear 11 that is mounted on a vertical shaft 12 at one side of the standard 3. The shaft 12 is journaled in a bearing-arm 13 projecting laterally from the standard 3 and in a bearing 75 in the frame top or table 1, below which latter it projects, and carries a bevel-gear 14 on its lower end in mesh with a loose bevel-gear 15 on a horizontal shaft 16. The shaft 16 is journaled in bearing-arms 17 depending from the under side of the table 1, and carries a worm-wheel 18, which meshes with a worm 19 on a drive-shaft 20, that is journaled in the lower end portion of the adjacent bearing-arm 17, and may have rotation 80 communicated thereto from any suitable source of power as desired.

A pair of vertical rocker-shafts 21, 21' are 85 journaled in the frame top or table 1 and in respective bearing-arms 22, 22', projecting laterally from the standard 3, and have their upper ends each provided with a forked head 23. Work feeding arms or levers 24, 24' are fulcrumed to one furcation of 90 each head 23 of the respective shafts 21, 21', as shown at 25, for horizontal swinging movements therewith, when rocked, and for vertical swinging movements relative thereto, for the purpose hereinafter described. The other or inner furcation of each head 95 23 serves merely as a stop or rest for limiting the downward swinging movements of the associated work feeding arm as shown, and has an upwardly projecting lug 23' for 100 coöperating with the arm fulcrum to brace the arm during its work feeding movements.

The lower end of one of the shafts 21, 21', the former, in the present instance, is provided below the frame top 1 with an arm 26, 110 which is connected by a rod 27 to a crank-arm 28 on a shaft 29 in such manner as to

cause rocking movements to be imparted to the shaft 21 from a revolution of such crank-arm. The shaft 29 is journaled at right angles to the shaft 16 in bearing-arms 30, which hang from the frame table bottom, and carries a large bevel-gear 31 in mesh with a smaller bevel-gear 32 on the shaft 16. The rock-shafts 21, 21' have arms 33 of equal length projecting therefrom and connected by a rod 34 to cause the shafts to have like rocking movements in unison when the one which is connected to the shaft 29 is rocked.

A work supporting platform or slideway 35 is disposed in the surface plane of the rotary table 4, which latter is disposed in an opening therein, and the rear arm 24 is intended, when swung forward, to move a work-piece 36, which may be a pail, can or other container or article, onto the table 4 in centered position relative to its opening 8, while the forward arm 24' is intended, when swung forward, to move a coated article from the table 4 to carrying-away position or onto a suitable conveyer means, not shown. In order to cause the rocker-arms 24, 24' to have their rearward or return movements in a plane which is elevated from the plane of their forward movements to enable them to pass over and then down at the rear of the respective workpieces to be next moved thereby, a suitable guide means is provided for imparting the requisite vertical swinging movements to the arms for such purpose.

The means provided in the present instance for guiding the vertical swinging movements of the arms 24, 24', consists in projecting the inner end of each arm beyond its fulcrum to form a short lever arm 37, and connecting this by a rod 38 to the outer end of a subjacent lever 39, which is fulcrumed for vertical rocking movements to the associated rock-shaft 21, 21', and has its inner end provided with a roller 40 that travels in a guide-member 41, mounted on the frame-table 1. This member has lower and upper segmental horizontal flanges 41^a and 41^b forming tracks on which the roller 40 of the association lever 39 has reverse directions of movement, as indicated by the arrows in Fig. 6. The ends of the upper track terminate short of the respective ends of the lower track and the forward end of the upper track, or that upon which the roller moves from the lower track, is provided with a hinged part 41^c which has its free end resting loosely by gravity upon the lower track and inclines rearward therefrom to the top surface of the upper track. As the roller moves forward on the lower track it raises the part 41^c to permit its passage thereunder, and upon its return or rearward movement travels up said part to the upper track 41^b and thence rearward thereon, thus

effecting a rocking of the lever 39 and a consequent elevating of the connected arm 24, 24', which elevated position is maintained during substantially the complete rearward stroke of the arm. When the work-feeding arm has approximately reached the limit of its rearward stroke the roller 40 passes over the rear end of the track 41^b and is guided to the lower track 41^a by an inclined flange 41^d which projects in the path of its movements from the member 41, thus lowering the associated work-feeding arm to the rear of the piece of work which it is intended to move forward on its forward stroke. The movements of the lever 37 are steadied by a dash-pot connection 39' between its outer end and the head 23.

The means employed for coating the work-pieces with any suitable coating substance, as paint, varnish, lacquer, bronze, or the like, consists in the provision of a plurality of air-brushes, one of which is designated A, and is shown as being mounted on a standard or suitable support at one side of the work supporting-table 4 and suitably adjusted to direct its discharge against the outer side of a work-piece mounted on said table, while another of such air-brushes which is designated B, is shown as being mounted in a suitable support within the hollow standard 8 and suitably adjusted to direct its discharge up into a work-piece which is mounted on the table 4 to effect a coating of the interior thereof when revolved.

While any suitable form of air-brush may be used in connection with my machine, I preferably employ air-brushes similar to the one shown in detail in Fig. 5. In this air-brush, 42 designates a barrel, which carries concentric inner and outer liquid and air nozzles 43 and 44, respectively, at its discharge end and has a plunger 45 working within its rear end portion and provided with a forwardly projecting needle or stem 46, which serves as a valve for closing the discharge orifice of the liquid nozzle 43, and is also adapted to clean such discharge orifice of accumulated matter when projected forward therein. A spring 47, which is mounted in a cage at the rear end of the barrel, acts on the plunger 45 to influence its forward movements, and the rearward movements of the plunger are limited by an adjusting screw 48. The interior of the air nozzle 44 has communication through a passage 49 with a valve-chamber 50, which has communication with a suitable source of air pressure supply and has a normally closed valve 51 therein. The barrel 42 is carried by a block 52 to which is fulcrumed a lever 53, as at 54, the short arm of such lever being connected by a bar 55 to the stem of the air valve 51, and also being connected by a bar 56 to a

130

pin 57, which projects from the rear end portion of the plunger 45 through registering slots in the barrel, whereby a rearward movement of the lower arm of the lever 53 will impart opening movements to both the air valve 51 and the liquid nozzle closing stem or valve 46. The point of connection of the bar 56 to the lever 53 is preferably more remote from its fulcrum than the point of connection of the bar 55 thereto in order to cause the valve 46 to have a greater opening movement than the valve 51. For a more complete description of the construction and operation of an air brush of this class reference is made to United States Letters Patent No. 1,045,266, dated November 26, 1912.

In order that the control lever 53 may be automatically operated to open the valves 46 and 51 at proper intervals, I connect the lower end of such lever through the medium of a link 58 to a plunger 59, which works in a cylinder 60 that is carried at the lower end of the block 52, air 25 under pressure being admitted through a nipple 61 to the end of the cylinder which is opposite to that from which the link 55 projects. Upon the admission of fluid pressure to the closed end of the cylinder the plunger 59 is moved in a direction to impart a valve opening movement to the lever 53, and upon the release of such pressure from the inner end of the plunger the springs, which normally act to seat the valves 46 and 51, cause a return of the valve controlling parts to normal position.

The air-brush A of the machine, which is intended to apply a coating material to the external surface of a work-piece on the table 4, is attached by a clamp 62 to a hollow standard 63, which rises from a side of the frame top 1 and has a cross-tube 64 mounted on its upper end with its interior in communication with the interior of the standard 63. Air or other air-brush actuating fluid is supplied to the standard 63 as hereinafter described and through it to the cross-piece 64, and thence through a tube 65 to the air-valve chamber 50 of the instrument, and also through a tube 66 and nipple 61, to which it attaches, to the interior of the cylinder 60 of the instrument. Paint, varnish or other surface coating matter, whether of a liquid or powdery nature, may be applied to the interior of the brush barrel 42 through a tube 67, which loads from any suitable source of supply and attaches to a nipple 42' on the barrel 42. The cross-piece 64 is shown as being provided with a plurality of valved nipples 68 to which the tubes 65 and 66 may be attached for connecting the supply tube 64 to any desired number of spraying instruments, as the size or nature of the work to be coated may require the use of a plurality 60 of air brushes in order to coat the entire ex-

ternal surface thereof at a single operation. When more than one of the spraying instruments are employed they are mounted on the standard 63 and adjusted relative thereto to direct their discharges in proper position 70 upon the work. The air-brushes are adjustably attached to their respective clamps 62 by the insertion of a retaining screw 69 (see Fig. 2) through an aperture 70 in the block 52 and threading it into the clamp. 75

The air-brush B, which is mounted within the standard 4, has its clamp 62 attached to a cross-bar 71, which is attached at its ends to opposite sides of said standard and has its air-supply tubes 65 and 66 attached to a tube 72, which branches from a tube 73 that leads to and feeds air to the standard 63. The surface-coating supply-tube 67 of the brush B leads from any suitable source of supply. The tube 73 attaches to a valve 83 chamber 74 which is supported above the frame top 1 by a hollow standard 75 that is mounted thereon and has communication through a supply pipe 76 with any suitable source of fluid pressure supply. The valve 90 chamber 74 has a valve 77 (see Fig. 4), which normally seats therein to close the communication between the supply pipe 76 and the outlet pipe 73, and also has a valve 78, which is normally seated to close communication between the interior of said chamber and the atmosphere through an exhaust passage 79. The stems of the valves 77 and 78 project downward through the bottom walls of the chamber 74 and into the 100 interior of the standard 75 with their lower ends in respective register with the vertically movable push-rods 80 and 81. These push-rods work through bearings in the frame top 1 and are provided above such 105 bearings with shoulders 82 for limiting their lowering movements therein. Upon a raising of the push-rods they act against the lower ends of the respective valve stems to effect an unseating of the valves against the 110 seating influence of the valve bearings 83.

The means employed for imparting properly timed valve opening movements to the push-rods 80 and 81 comprises, in the present instance, a pair of cam disks 84 and 85, which are fixed to the shaft 29 and upon which rollers 86 work and communicate movements through their carrying arms 87 to the respective push-rods below which they are located. The roller carrying arms 87 are pivoted to studs 88, which project downward from the under side of the frame top 1 at one side of said push-rods, as shown in Fig. 7. The peripherally raised portions 84' and 85' of the respective disks 84 and 85 are 115 so relatively arranged and proportioned that the disk 84 acts to unseat the valve 77 to permit the passage of air under pressure from the supply pipe 76 to the pipe 73 and its connections with the air controlled parts 120 125 130

of the respective air brushes, whereby to actuate the plungers 59 thereof to open their valves 46 and 51 and to discharge air through the air nozzles 43 thereof during a rearward swinging movement of the work feeding arms 24 and 24', while the disk 85 acts to unseat the valve 78 upon a closing of the valve 77 and during the forward or feeding strokes of the arms 24 and 24' to cause a 10 stopping of the spraying action of the brushes. The shaft 29 also carries a cam-member 89 upon the cam side of which a roller 90 that is carried at one end of a bell crank lever 91 works, said lever being fulcrumed to a bearing arm 92 depending from the under side of the frame top 1, and having its other end in loose forked engagement with the shiftable member of a friction clutch 93. The shiftable member of the 15 clutch is feathered to the shaft 16 and is normally held in frictional engagement with its companion on the loose bevel gear 15 by the action of the spring 94. The rotary work supporting table 4 and the shaft 29 are so 20 geared to the common drive means that the table 4 is caused to make two revolutions to each revolution of the shaft 29. In order to cause the table to stand stationary during one-half of a revolution of the shaft 29 or 25 during the period of the forward work feeding movements of the arms 24, 24' the cam 89 is provided on a side thereof with which the roller 90 coacts with a semi-circular laterally projected portion which, when the 30 roller 90 is traveling thereon, moves the lever 91 and shiftable member of the clutch 93 to released position against the tension of the spring 94. It is thus apparent that the work supporting table 4 has complete revolutions intermittently communicated thereto, 35 with its periods of rest substantially equal in length to the period of revolution so that the table stands at rest during the forward work feeding movements of the arms 24, 24' 40 and rotates during the rearward or return movements of such arms.

The operation of my invention is as follows: The drive shaft 20 being set in motion, rotation is communicated to the shaft 16 and through it and the gears 31 and 32 to the shaft 29. At each revolution of the shaft 29 the work feeding arms 24 and 24' are swung forward, the former to move a work-piece 36 to coating position upon the 55 rotary table 4 and the latter to move a coated work-piece from such table to carrying-away position on the platform 35, and then to return such arms to starting position, one-half of a revolution of the shaft 29 being consumed in the forward strokes and one-half in the rearward strokes of such arms. During the forward strokes of the arms 24, 24' the rollers 40, which are carried by the respective arm guiding levers 39, 60 travel on the lower tracks 41^a of the respec-

tive guide members 41, and upon the rearward movements of such arms said rollers pass up the inclined portions 41^c to and then rearward on the upper tracks 41^b of the guide members to communicate corresponding rocking movements to the levers 39 and arms 24, 24' to raise the work engaging ends of such arms above the work-pieces which were respectively moved thereby on their forward strokes. When the arms 75 have moved to the rear of the next work-pieces to be engaged and moved forward thereby, the rollers 40 drop from the upper guide tracks 41^b to the roller tracks 41^a, thus effecting a lowering of said arms to 80 work engaging positions. During the rearward movements of the work feeding arms the work supporting table 4 has at least a complete revolution communicated thereto from the shaft 16 due to the roller 90 on 85 the clutch shifting lever 91 riding on the reduced semi-circular portion of the cam 89, thus permitting the spring 94 to effect an engagement of the clutch 93. The cam 84 also acts during the rearward movements 90 of said arms to raise the push-rod 80 to unseat the air-inlet valve 77, thus permitting the passage of operating air or other fluid under pressure to the air brushes employed, a portion of the fluid passing into the cylinders 60 to impart valve opening movements to the plungers 59 and levers 53 and a part passing to the valve chambers 50 of the spraying instruments, and thence through the fluid discharge nozzles 44 thereof to draw the surface coating material from the barrel 42 through its nozzle 43 and discharge it in fine spray form upon the work, as is well understood in the art. The arrangement and number of the air-brushes is 95 such that the complete interior and exterior surfaces of an article are coated by matter discharged therefrom, it, of course, being understood that the under side of the article being coated is open to permit an interior 100 spraying thereof by the sprayer or sprayers B. At approximately the time of completion of the rearward stroke of the work feeding arms, the roller 90 on the clutch shifting lever 91 moves onto the broadened portion of its cam member 89 to release the engagement of the clutch 93 and stop the rotation of the work supporting table, and the roller 86 on the cam 84 rolls onto the reduced peripheral portion of such cam, thus 105 permitting a lowering of the push-rod 80 and closing of the air-inlet valve 77 to stop the spraying action of the sprayer, said valve being maintained in closed position during the forward strokes of the work feeding arms. Immediately after the air-inlet 110 valve operating roller 86 on the cam 84 lowers to permit a closing of such valve the exhaust-valve operating roller 86 on the cam disk rides onto the peripherally broad- 115

125

130

ened portion of its disk, thus opening the exhaust valve 78 and maintaining the same open during the forward strokes of the work feeding arms.

5 It is apparent that I have provided a simple and efficient machine which is automatically operable to intermittently feed work-pieces to and from a rotatable work support, to impart rotation to the work support when an article is mounted thereon, and which 10 employs air brushes that are automatically operable to apply a coating material to either or both the inner and outer surfaces of the article during a rotation of the work support.

15 It is found in practice that a machine of this character is admirably adapted for use in connection with the painting or surface coating of containers or other similar 20 articles, and that the coating thereof is accomplished with greater efficiency, rapidity and neatness than has heretofore been possible.

It is to be understood that the invention 25 is not limited to any specific construction or arrangement of the parts or to the number of air brushes employed except in so far as such limitations are specified in the claims.

30 Having thus described my invention, what I claim as new and desire to secure by Letters Patent, is,—

1. In a machine of the class described, a compound oscillatory work-feeding member, and means operable to impart work-feeding movements in one plane to the arm and to raise and move the work-engaging 35 part of the member in a different plane during its return movement and then to lower it to the rear of a work piece to be next moved thereby.

2. In a machine of the class described, a pair of work-moving arms capable of compound oscillatory work-feeding movements, and means for moving such arms to feed 45 separate work pieces in unison and then to return the arms to position to engage and feed work pieces.

3. In a machine of the class described a 50 pair of work-moving members capable of compound oscillatory movements, one member being adapted to move work pieces into position to be operated on and the other member being adapted to move work pieces 55 from such position, and means for imparting compound oscillatory movements to said members whereby they will engage and move respective work pieces forward and then move back over and to the rear of the 60 work pieces to be next engaged thereby.

4. In a machine of the class described, a 65 plurality of work-feeding arms mounted for compound oscillatory movements and adapted to successively act on a work piece to im-

part predetermined feeding movements there- to, and means for imparting compound oscillatory work-feeding movements to said arms and then to return the same to initial work feeding positions.

5. In a machine of the class described, a 70 table over which the work is fed, a plurality of arms mounted for horizontal and vertical oscillatory movements and adapted to successively act on work pieces to impart intermittent feeding movements thereto, and means for imparting horizontal feeding and 75 returning movements to the arms, and vertical swinging movements thereto during their returning movements to adapt them to pass over and to the rear of work pieces next 80 to be engaged thereby.

6. In a machine of the class described, a work support, a vertical rock shaft, an arm mounted for rocking movements with said shaft and for vertical rocking movements 85 relative thereto, means for imparting rocking movements to said shaft to move said arm to and fro to successively move work pieces to a predetermined position on said support, and means automatically operable 90 to impart vertical rocking movements to the arm when the shaft is rocked to raise the arm over and then lower it at the rear of a work piece next to be moved.

7. In a machine of the class described, a 95 rotatable work-supporting table, and mechanism automatically operable to intermittently rotate said table, and having a plurality of compound oscillatory arms which are moved to successively feed work pieces 100 onto and from said table when the table is at rest.

8. A machine of the class described having a horizontally rotatable work-supporting part provided with an axial opening over 105 which a work piece may be disposed, means for applying a surface coating material in spray form through said opening and into a work piece disposed thereover and means for applying a surface coating material in spray 110 form to the exterior surface of a work piece mounted over said opening.

9. An intermittently rotatable work-supporting table having a centrally disposed vertical opening therein, means automatically operable to apply a surface coating material in spray form through said opening and into a registering open end of a work piece, and means automatically operable upon a rotation of said table for applying a surface coating material in spray form 115 to the exterior surface of a work piece which is supported by said table.

10. In combination, means operable to discharge a surface coating material in 120 spray form and having control means, and fluid pressure actuated means for opening said control means.

11. In a machine of the class described, an intermittently rotatable work support 125

- having an opening therein, means operable to successively move articles onto the support over said opening transversely thereof and then from the support, and means automatically operable upon a rotation of the work support to apply a surface coating material in spray form through said opening and into a superposed article and also on the exterior surface of such article.
12. In a machine of the class described, a horizontal work support, a work feeding member, and an air-brush, and mechanism for moving said member to feed work onto the support transversely thereof, for rotating such support when a work piece is disposed thereon, and for operating the air-brush simultaneously with the rotation of the support to apply a surface coating material in spray form to a work piece mounted on the support.
13. In a machine of the class described, a horizontally rotatable work support, an air-brush, and mechanism automatically operable to intermittently rotate said support, and means for successively moving work pieces onto and from the support transversely thereof when the support is at rest and for operating the air-brush to apply a surface coating material to articles when mounted on and rotating with the support.
14. In a machine of the class described, a hollow standard, a work-supporting table mounted over said standard and having an annular flange fitting down over the standard, said table having a central opening in communication with the hollow of the standard, means coating with said flange to communicate rotary movements to the table, and means having a part within the standard and automatically operable to discharge a surface coating material in spray form through the table opening and into an article supported on the table through said opening.
15. In a machine of the class described, a hollow upright standard, a work-supporting table mounted for rotary movements on said standard and having a central opening in communication with the interior of the standard and an annular depending flange without said opening and fitting down around the upper end portion of the standard, means for imparting intermittent rotation to said table relative to the standard, means for intermittently feeding work pieces onto the table over said opening and from the table, and means for spraying a surface coating material onto the interior surface of an article when mounted on the table over the opening therein.
16. In an article coating machine, a vertical standard, a work-supporting table mounted for horizontal rotary movements on said standard, means connected with and automatically operable to impart intermit-

tent rotary movements to the table, and means for moving a work piece transversely of the table to central position thereon when the table is at rest.

17. In an article coating machine, a vertical standard, a work-supporting table mounted for horizontal rotary movements on said standard, means connected with the table for imparting intermittent rotary movements thereto, and mechanism automatically operable during a period of rest of the table to move a work piece from the table and to move a succeeding work piece to central position on the table.

18. In a machine of the class described, a vertical standard, a horizontally rotatable work-supporting table mounted thereon, means automatically operable to intermittently rotate the table, mechanism automatically operable to move a work piece from the table and to move a successive work-piece to central position on the table during a period of rest of the table, and mechanism automatically operable to apply a coating material in spray form to a work-piece on the table during a period of rotation of the table.

19. In an article coating machine, a horizontally rotatable work-supporting table, and mechanism connected with and automatically operable to cause the table to have alternate rotating and resting periods and to successively move work pieces onto and from the table during resting periods thereof, the work pieces being fed onto the table from one side of its axis and from the table at the opposite side of its axis.

20. In a machine of the class described, a horizontally rotatable work-supporting table, means connected with the table for causing it to have alternate rotating and resting periods, and mechanism having a compound oscillatory member and automatically operable to feed a work piece onto the table during a resting period thereof and to return to position to engage a succeeding work piece during a rotating period of the table.

21. In a machine of the class described, a horizontally rotatable work-supporting table having a stationary axis and a centrally disposed opening, means for imparting intermittent rotation to the table, and mechanism automatically operable to intermittently move successive work pieces across the table from one side to the other of its axis, each work piece standing at rest over the table opening during a rotating period of the table, and means automatically operable to apply a coating material in spray form to the interior of a work piece through the table opening when a work piece is standing thereover.

22. In a machine of the class described, a horizontally rotatable work-supporting table

- having a centrally disposed opening therein, means for imparting intermittent rotary movements to the table, mechanism for imparting intermittent feeding movements to work pieces across the table from one side to the other of its axis, each work piece being permitted to rest over the table opening during a rotating period of the table, and means automatically operable to apply in spray 5
- 10 form a coating material to the inner and outer surfaces of an article when standing over the table opening, the inner coating being applied through the table opening.
23. In a machine of the class described, a 15 vertical rock shaft, an article feeding-arm projecting transversely from said shaft and adapted to have horizontal rocking movements therewith and vertical rocking movements relative thereto, a lever member ful-
- 20 crumed to said shaft for horizontal rocking movements therewith and vertical rocking movements relative thereto, means guiding said lever to cause it to have predetermined vertical rocking movements when
- 25 rocking with the shaft, and connection between said lever and arm for communicating similar vertical rocking movements from one to the other.
24. In a machine of the class described, a 30 rock shaft, two members carried by said shaft for rocking movements therewith and for rocking movements relative thereto in a plane which is transverse to the shaft rocking movements, means coacting with one of
- 35 said members to impart predetermined rocking movements thereto when rocking with the shaft, and means connecting said members to cause them to have like rocking movements transverse to the shaft rocking
- 40 movements.
25. In a machine of the class described, a rock shaft, two lever members carried by said shaft for rocking movements therewith and for rocking movements relative 45 thereto in the longitudinal plane of the shaft, one of said members serving as a feeder-arm, guide means for guiding the other of said members to cause it to have predetermined rocking movements longitudinally of the shaft when rocking with the
- 50
- shaft, means connecting said members to cause them to have like rocking movements longitudinally of the shaft, and means for retarding said latter rocking movements of the members. 55
26. In a machine of the class described, a horizontally rotatable work-supporting table, a vertical shaft at one side of the table, a pair of lever members carried by the shaft for rocking movements therewith and for rocking movements longitudinal thereof, one of said members constituting a work-feeding arm and projecting over said table, means coacting with the other of said members to impart rocking movements thereto longitudinally of the shaft when rocked with the shaft, means connecting said members to cause them to have like rocking movements longitudinally of the shaft, and mechanism operable to rock 60
- 65 said shaft.
27. In a machine of the class described, a vertically stationary horizontally rotatable work-supporting table, and mechanism having a plurality of work-feeding arms automatically operable to have parallel rocking movements to impart successive work feeding movements to a work piece across the 70 table top. 75
28. In a machine of the class described, a horizontally rotatable work-supporting table, a pair of rock shafts disposed at one side of the table, a work-feeding arm carried by each shaft for rocking movements therewith and longitudinally thereof, means operable to impart predetermined rocking movements to said arms when the shafts are rocked, and means for imparting rocking movements in unison to the shafts to operate said arms to impart successive feeding 80
- 85 movements to a work piece across the table top.
- In testimony whereof, I have hereunto signed my name to this specification in the presence of two subscribing witnesses.

THOMAS A. DE VILBISS.
